UNITED STATES PATENT OFFICE.

MARTIN M. ANTHONY, OF HARRISONVILLE, MISSOURI.

TRANSFERRING DEVICE FOR RAILWAY MOTOR CARS.

Application filed April 9, 1924. Serial No. 705,318.

To all whom it may concern:

Be it known that I, MARTIN M. ANTHONY, a citizen of the United States of America, and resident of Harrisonville, in the county 5 of Cass and State of Missouri, have invented certain new and useful Improvements in Transferring Devices for Railway Motor Cars, of which the following is a specification.

10 This invention relates to railway track equipment, and particularly to a switch or device adapted to remove the cars of section crews from the said track and to replace the said cars to the track; the said 15 device being intended to relieve the operators of burdens incident to the removal and replacement of cars as now commonly used.

It is a well known fact to those skilled 20 in the art that the conventional motor cars used by section crews are quite heavy and to derail or rerail or turn such cars imposes a burden on the crews which this invention is designed to modify.

25 Furthermore, the invention prevents accidental dropping of the car between the ties and tends to avoid damage to the motor of the car which would be occasioned by jolting, and it also obviates the twisting and 30 springing of axles of the car, and avoids danger to the workmen.

It is an object of this invention, therefore, to produce a device which will permit the car to be readily turned, the said device 35 being intended to support the heavy end of the car while it is being transferred to or from the rail; the said device necessitating only that the light end of the car be lifted by the crew and carried around while 40 the wheels of the heavy end of the car are supported and rolled on tracks provided for use in the operation just described.

It is a further object of this invention to produce rails adapted to be stationed practically transversely of the rails of an ordinary railway track, and to provide plates on which wheels of the car to be changed may rest while the opposite wheel is traveling along one of the curved rails, making 50 it possible to transfer the wheel from one rail to the opposite rail of the railway track without heavy lifting or liability of the car being dropped between the rails and ties.

With the foregoing and other objects in

view, the invention consists in the details 55 of construction, and in the arrangement and combination of parts to be hereinafter more fully set forth and claimed.

In describing the invention in detail, reference will be had to the accompanying 60 drawings forming part of this application wherein like characters denote corresponding parts in the several views, and in which—

Figure 1 illustrates a plan view of a 65 fragment of the railway track showing a device embodying the invention applied thereto;

Figure 2 illustrates a side elevation thereof; 70

Figure 3 illustrates a sectional view on the line 3—3 of Fig. 1; and

Figure 4 illustrates a sectional view on the line 4—4 of Fig. 1.

In these drawings, 5 and 6 denote plates 75 or platforms which constitute supports for flanges of wheels of a motor car while the car is being turned. The plates have curved rails 7 and 8 connected to them, respectively, and the rails curve oppositely and diverge 80 from a plate 9 to which they are secured by fastenings 10 such as rivets, bolts or the like. The rails 7 and 8 are likewise secured to their respective plates by similar fastenings, but as the type of fastening is not 85 material, further detailed description thereof is believed unnecessary.

The rails and plates are supported by shoes or hooks 11 and 12 that embrace the head of one of the rails of the track, and 90 the plate 9 is associated with a shoe or hook 13 that embraces the head of the opposite rail of the track, so that when the device is applied to the rails of the track as shown in Fig. 1, there are two curved rails which 95 diverge and may be employed for supporting the wheels of the motor car when the same is to be turned, it being understood that the light end of the car will be carried around by the crew while the wheels of the 100 heavier end are being supported by a plate and rail, according to the direction of travel imparted to the car by the crew.

The shoes 6 have loops or eyes 14 which are engaged by the angularly disposed ends 105 of the track extension 15 on which the wheels of cars may travel on an incline from the ground to the top of the shoe in order

that the said wheels may be placed on the transversely disposed rails when the car is to be replaced on the railway track.

I claim:

- 5 1. In a transferring device for railway motor cars, oppositely diverging rails adapted to extend between the rails of a railway track, means for supporting the diverging ends of the rails in proximity to 10 one of the rails of the track, and means for supporting the converging ends of the rails in proximity to the opposite rail of said track, substantially as described.
- 15 2. In a transferring device for railway motor cars, oppositely curved rails adapted to occupy positions between rails of a railway track, shoes adapted to embrace the head of one of the rails for suspending the ends of the diverging rails in proximity to

the rail of the track, and a member 20 adapted to embrace the other rail of the track to which the converging ends of the said rails are connected, substantially as described.

- 25 3. In a transferring device for railway motor cars, oppositely curved rails adapted to occupy positions between rails of a railway track, shoes adapted to embrace the head of one of the rails for suspending the ends of the diverging rails in proximity to 30 the rail of the track, a member adapted to embrace the other rail of the track to which the converging ends of the said rails are connected, and platforms constituting supports for flanges of the rail at approximately the junction of the first mentioned rails and their supporting means.

MARTIN M. ANTHONY.
